US0D1042142S

(12) **United States Design Patent** (10) Patent No.: **US D1,042,142 S**
(45) Date of Patent: ** Sep. 17, 2024

(54) **BOTTLE**

(71) Applicant: **Kraft Foods Group Brands LLC**,
Chicago, IL (US)

(72) Inventors: **Daniel Taek Kim**, Washington
Township, NJ (US); **Trond Erik
Tollefson**, London (GB); **Stuart M.
Leslie**, Larchmont, NY (US)

(73) Assignee: **Kraft Foods Group Brands LLC**,
Chicago, IL (US)

(**) Term: **15 Years**

(21) Appl. No.: **29/925,841**

(22) Filed: **Jan. 26, 2024**

Related U.S. Application Data

(62) Division of application No. 29/821,878, filed on Jan.
4, 2022, now Pat. No. Des. 1,018,304.

(57) **CLAIM**

The ornamental design for a bottle, as shown and described.

DESCRIPTION

FIG. 1 is a top, front perspective view of a bottle in accordance with our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the figures show portions of the bottle that form no part of the claimed design. The dash-dot lines indicate an unclaimed boundary and form no part of the claim.

1 Claim, 5 Drawing Sheets
